UNITED STATES PATENT OFFICE.

AMANDA G. HAYNES, OF BUFFALO, NEW YORK.

SLEEVE-PROTECTOR.

SPECIFICATION forming part of Letters Patent No. 741,133, dated October 13, 1903.

Application filed March 25, 1903. Serial No. 149,537. (No model.)

To all whom it may concern:

Be it known that I, AMANDA G. HAYNES, a citizen of the United States, residing at Buffalo, in the county of Erie and State of New York, have invented new and useful Improvements in Sleeve-Protectors, of which the following is a specification.

This invention relates to a sleeve-protector designed more particularly for the use of persons engaged as stenographers, bookkeepers, &c. As heretofore constructed, this protector consisted, essentially, of a tubular body of transparent celluloid having a straight front end, an oblique rear end, a longitudinal joint extending from the front to the rear end of the body in the shortest or innermost part of the body and in the median line thereof, and a lacing connecting the parts of the body on opposite sides of the joint.

In using the protector the same is applied to the arm so that the inner or receding part of the oblique end is arranged adjacent to the hollow of the elbow, while the outer or salient part of the oblique end extends to the knuckle of the elbow, thereby affording the fullest protection for the sleeve against soiling. The location of the longitudinal seam or joint in the shortest part or median line of the body has been found to be objectionable, because it is liable to catch on the edges of books, desks, or other objects which are handled or upon which the arm rests in using the books and the lower garments are also chafed and injured by the joint of the sleeve-protector rubbing against the same in swinging the arm.

The object of this invention is to improve the construction of the sleeve-protector so as to eliminate this objectionable feature.

In the accompanying drawings, Figure 1 is a perspective view showing my improved sleeve-protector applied to an arm. Fig. 2 is a perspective view of the body of the sleeve-protector. Fig. 3 is a top plan view of the same. Fig. 4 is a view of a spread-out blank from which the sleeve-protector body is constructed.

Similar letters of reference indicate corresponding parts throughout the several views.

A represents the tubular body of the sleeve-protector, constructed, preferably, of a sheet of transparent elastic celluloid which is com-

paratively stiff and smooth, so as to slide easily over the surface upon which the arm rests. Moreover, by constructing the body of the protector of transparent celluloid the same can be readily cleaned and the garment is visible through the protector, so that the use of the latter is not unsightly. The body of the sleeve-protector is formed from an unsymmetrical flat blank or sheet having a straight front end b, an irregular rear end C, consisting of a convex lobe or salient edge e² and a concave or receding edge e' and two straight forwardly-converging sides d d', said lobe being offset from the longitudinal center of the blank, as shown in Fig. 4. Upon rolling this blank the same forms a tubular body having a straight front end at b, an oblique or beveled rear end at C, a short inner side extending from the front end to the receding edge e' of the rear end, a long outer side extending from the front end to the salient edge e² of the rear end, and a longitudinal joint e between the side edges, which is located between the shortest part of the inner side and the longest part of the outer side of the body, as shown in Fig. 2. In its finished condition the tubular body is symmetrical on opposite sides of a median line f drawn lengthwise through the shortest part of the inner side and the longest part of the outer side of the body, and the longitudinal joint of the body is located on one side of this median line, as shown in Fig. 2.

The protector is applied to the arm so that the receding or innermost point e' of the oblique end of the body is arranged adjacent to the hollow of the elbow, while the outermost or salient part e² of this end extends to the knuckle of the elbow, thereby covering as much as possible that part of the sleeve which is most liable to be soiled. The longitudinal joint of the body is arranged above its median line, so that when the protector is applied to the arm the joint is located on the upper part of the arm, as shown in Fig. 1, where the same is not liable to interfere with the books which are being handled nor with the supports on which the arm rests. Furthermore, this location of the joint in the body of the protector prevents the same from coming in contact with the lower garments and wearing the same unduly when swinging the

arm. The longitudinal edges of the body may be united to close the joint between the same in any suitable manner, preferably by means of a lacing-cord *g*, which is threaded through 5 two longitudinal series of openings formed in the opposing side edges of the body for this purpose. Means may also be provided for retaining the protector in its proper place on the arm, the means for this purpose shown in 10 the drawings consisting of a retaining-cord *h*, connected at one end with the inner end of the body and forming, preferably, a continuation of the lacing-cord, and a clasp *i*, arranged on the outer end of the retaining-cord and 15 adapted to grasp the sleeve above the elbow, as shown in Fig. 1.

I claim as my invention—

1. A sleeve-protector comprising a tubular body having an oblique rear end forming a 20 short inner side and a long outer side and

having a longitudinal joint arranged between the shortest part of the inner side and the longest part of the outer side of the body, substantially as set forth.

2. A blank for a sleeve-protector having a 25 straight front end, two straight forwardly converging sides, a salient part or lobe arranged on its rear end and offset from the longitudinal center of the blank, and a row of perforations along the side edges, said blank 30 when rolled forming a tubular body having a short inner side, a long outer side and a longitudinal joint located between the inner and outer sides, substantially as set forth.

Witness my hand this 24th day of March, 35 1903.

AMANDA G. HAYNES.
